RAILWAY CAR DIAPHRAGM FACE PLATE MOUNTING

James F. Monger, Chicago, Ill.

Application February 9, 1949, Serial No. 75,435

5 Claims. (Cl. 105—21)

1

This invention relates to improvements in car construction, and more particularly the diaphragm face plate and buffer construction of railway passenger cars of the vestibule type.

One object of the invention is to provide simple and efficient means for mounting the diaphragm face plate member of a car on the buffer platform face plate, whereby access to the parts for the purpose of repair or replacement may be readily had without necessitating removal of the diaphragm face plate.

A more specific object of the invention is to provide a mounting for diaphragm face plates, comprising brackets fixed to the lower end portions of the face plates and detachably secured to the inner sides of the buffer platform face plates, whereby the platform face plates may be readily removed without detaching the diaphragm face plates from the car.

Other objects of the invention will more clearly appear from the description and claims hereinafter following.

In the accompanying drawings forming a part of this specification, Figure 1 is an elevational view, partly broken away of the vestibule end portion of a passenger car, illustrating my improvements in connection therewith. Figure 2 is a top plan view of the buffer face plate shown in Figure 1. Figure 3 is a broken vertical sectional view, corresponding substantially to the line 3—3 of Figure 1. Figure 4 is a broken top plan view, on an enlarged scale, of the structure at the lower right hand corner of Figure 1, with the diaphragm face plate omitted. Figure 5 is a front elevational view of one of the brackets by which the diaphragm face plate is attached to the buffer face plate. Figure 6 is a side elevational view of Figure 5, looking from right to left in said figure. Figure 7 is a broken front elevational view of Figure 4, with the bracket for the diaphragm face plate omitted. Figure 8 is a top plan view of Figure 7. Figure 9 is a view, similar to Figure 1, illustrating another embodiment of the invention. Figure 10 is a broken rear elevational view, on an enlarged scale, of the hinged connection between the outer and inner members of the diaphragm face plate, at the upper right hand side of Figure 9. Figure 11 is a broken rear elevational view, on an enlarged scale, of the hinged connection between the outer and inner members of the diaphragm face plate at the lower right hand side of Figure 9. Figure 12 is a top plan view of the hinge bracket at the lower left hand side of Figure 9.

In carrying out my invention, as illustrated

2

in Figures 1 to 8 inclusive of the drawings, I provide broadly a one piece buffer face plate A, a diaphragm face plate B having securing brackets C—C fixed to the bottom portions thereof and attached to the buffer face plate A.

The buffer face plate A, which is preferably in the form of a casting, has a horizontal top wall 10 and a depending front wall 11 at the front edge thereof. The top wall is reinforced by bottom ribs 12—12, shown in dotted lines in Figure 2, extending lengthwise of the car, and the front wall is reinforced by spaced horizontal ribs 13—13, shown in dotted lines in Figure 1, the ribs 13—13 being at the rear side thereof and extending transversely of the car. The buffer face plate A is carried by the usual end platform of the car, not shown, and cooperates with the usual central buffer stem of the buffering mechanism in a well-known manner, and is supported by side stems of the buffering mechanism, not shown, which are pivotally connected thereto, as is common practice in passenger car construction.

The depending front wall 11 of the buffer face plate projects beyond the opposite side edges of the top wall 10, as indicated at 14—14, the front faces of said projecting portions being in alignment with the front face of the wall 11 proper. The horizontal top wall 10 is of the outline shown in Figure 2, having a transverse straight rear edge 15, forwardly extending, diverging side edges 16—16, and straight side edges 17—17 forwardly of the edges 16—16, at opposite sides of said top wall.

The diaphragm face plate B comprises a transverse upper section 18 and laterally spaced leg-like sections 19—19 depending from said upper section at opposite ends thereof. The upper section 18 of the face plate B is supported in a well known manner on the end wall of the car, which end wall is indicated by 20 in Figure 1. The means for supporting the face plate B at its upper end comprises a diaphragm spring 21 of the leaf type, having its opposite ends guided in brackets 22—22 fixed to the end wall 20 of the car, and anchored midway between its ends to the rear side of the top section of the face plate B. The leglike sections 19—19 of the face plate B are secured at their lower ends to the buffer face plate A by the brackets C—C, which are welded to the rear sides of these sections of the diaphragm face plate.

As shown in Figures 3, 4, 5, and 6, each bracket C is in the form of a steel casting comprising a rectangular, relatively heavy, platelike main body

portion 23 having a right angular, horizontally disposed, forwardly projecting top flange 24 and a right angular, vertically extending flange 25 at the outer side edge thereof, as seen in Figure 3. Upstanding from the flange 24 is a winglike plate section 26 which is offset inwardly from the front edge of said flange, as shown in Figure 6. The amount of offset of the section 26 is substantially the same as the thickness of the corresponding leg 19 of the diaphragm face plate B. The wing 26 is preferably reinforced by vertically extending ribs 27 on the rear side thereof. The brackets C—C are fixed to the inner sides of the leglike sections 19—19 of the diaphragm face plate B, the flat side of the wing 26 of each bracket C abutting the inner side of the corresponding leglike section with the lower edge of said section supported on the ledge formed by inwardly offsetting the wing with respect to the outer edge of the flange 24 of the bracket, the wing 26 being preferably welded to the leglike section 19.

The brackets C—C are secured to the outwardly projecting portions 14—14 of the buffer face plate A at the rear sides of said projections, with the top flange 24 of each bracket engaged over the top edge of the corresponding projecting portion 14 and the outer vertical flange engaged over and abutting the vertical end edge of said projecting portion. The rectangular body portion 28 of each bracket C is preferably provided with a plurality of projecting bosses 28—28 on its inner side, which are in abutment with similar bosses 29—29 on the rear side of the corresponding projecting portion 14 of the buffer face plate. The bosses 28—28 and 29—29 have aligned openings therethrough to receive any well-known type of securing elements 30—30 for fixing the brackets to the buffer face plate A. These securing elements may be in the form of bolts or rivets.

As will be evident, the legs 19—19 are secured to the rear sides of the extensions of the buffer face plate A, thus permitting removal or detachment of the buffer face plate A by removal of the securing elements 30—30 without disturbing the diaphragm face plate, which, in those constructions where the diaphragm face plate is attached to the front or outer side of the buffer face plate, must be entirely removed from the car before the buffer face plate can be removed or replaced.

Referring next to the embodiment of the invention illustrated in Figures 9, 10, 11, and 12, my improvements are illustrated as embodied in a diaphragm face plate construction, particularly adapted for streamlined cars. As shown in these figures, the diaphragm face plate comprises a central section 31 and hinged outer side sections 32 and 33. The buffer face plate 34, on which the diaphragm face plate is supported, is substantially identical with the buffer face plate A hereinbefore described, having projections 35—35 at opposite sides forming continuations of the front wall of the buffer face plate and corresponding to the projections 14—14 hereinbefore described. The central section 31 of the diaphragm face plate comprises a transverse upper portion 36 and leglike members 37—37 depending from said upper portion. Each outer side section 32 and 33 comprises an upright outer member 38 and inwardly projecting top and bottom arms 39 and 40 on said upright member. The top arm 39 of each side member is connected to the corresponding end of the portion 36 of the central section 31 by the usual hinge 41, the hinged plates of

which are welded to the portion 36 and the arm 38, respectively. The portion 36, members 37—37, member 38, and arms 39 and 40 of the central section 31 and of the outer side sections 32 and 33 of the buffer face plate are preferably formed of relatively thin material, which is reenforced along the edges by being flanged, as shown in dotted lines in Figure 9 and as indicated by 42, thereby greatly reducing the weight of the diaphragm face plate structure.

The central section 31 of the diaphragm face plate is fixed to the buffer face plate 34 by brackets D—D welded to the inner sides of the bottom ends of the legs 37—37 of the section 31 and riveted or bolted to the side projections 35—35 of the buffer face plate 34. The brackets D—D are similar to the brackets C—C hereinbefore described, with the exception that the main body portion of each bracket D, which portion is indicated by 43 and corresponds to the main body portion 23 of the bracket C, is provided with a laterally outwardly extending arm 44 forming a hinged plate and having a hinge eye 45 at its extremity. The bottom arm 40 of each outer side section of the diaphragm face plate has a hinge leaf 46 welded to its inner side, the hinge leaf 46 being provided with a hinge eye 47 at its outer end connected with the hinge eye 45 of the arm 44 of the corresponding bracket D by a hinge pin 48.

I claim:

1. In a vestibuled railway car, the combination with a buffer face plate at the end of the car provided with laterally extending wings at opposite sides thereof having their inner sides facing the body of the car; of a diaphragm face plate having spaced side members; a securing bracket fixed to the lower end of each side member, each bracket including a platelike section engaging the inner side of the corresponding wing, a horizontal portion supported on top of the buffer face plate, and a section upstanding from said platelike section and welded to the corresponding side member of the diaphragm face plate; and removable means extending through said wings and platelike sections of said brackets for securing the brackets to the buffer face plate.

2. In a vestibuled railway car, the combination with a buffer face plate at the end of the car provided with laterally extending wings at opposite sides thereof having their inner sides facing the body of the car; of a diaphragm face plate having spaced side members; a securing bracket fixed to the lower end of each side member, each bracket including a platelike section engaging the inner side of the corresponding wing and having a horizontal top flange and a vertical side edge flange engaged respectively over the top and vertical outer side edges of said wing; a platelike arm upstanding from the horizontal top flange of each bracket and welded to the corresponding side member of the diaphragm face plate; and means extending through said wings and platelike sections of said brackets for securing the brackets to the buffer face plate.

3. In a vestibuled railway car, the combination with a buffer face plate at the end of the car provided with laterally spaced wings at opposite sides thereof having their inner sides facing the body of the car; of a diaphragm face plate at the end of the car comprising a central section and hinged side sections, the central section including a pair of laterally spaced side members; a securing bracket fixed to the lower end of each side member, said brackets engaging the inner

sides of the wings of said buffer face plate, each bracket including a horizontal flange engaged over the top of and supported by said wing; means extending through said wings and brackets for securing the brackets to the buffer face plate; laterally outwardly extending hinge arms on said brackets rigid therewith; and means pivotally connecting said side sections of the diaphragm face plate to the outer ends of said hinge arms.

4. In a vestibuled railway car, the combination 10 with a diaphragm face plate at the end of the car; of a buffer face plate at said end of the car provided with laterally projecting portions having the inner sides thereof facing the body of the car; brackets fixed to the lower end portion 15 of said diaphragm face plate, said brackets having upstanding plate sections welded to the face plate and securing portions depending from said plate sections engaging the inner sides of said projections of the buffer face plate, said upstanding plate sections having lengthwise extending reenforcing ribs thereon projecting at right angles to the plane of said plate sections; and fastening elements extending through said laterally projecting portions of the buffer face plate and 20 securing portions of the brackets for detachably securing the brackets to said buffer face plate.

5. In a vestibuled railway car, the combination with a buffer face plate at the end of the car provided with laterally extending wings at opposite sides thereof having the inner sides thereof facing the body of the car; of a diaphragm face plate having spaced side members; a securing bracket fixed to the lower end of each side member, each of said brackets having a securing portion located below the corresponding side member engaging the inner side of the corresponding wing of the buffer face plate; and means extending through said wings and securing portions of the brackets for securing the brackets to the buffer face plate.

JAMES F. MONGER.
